UNITED STATES PATENT OFFICE

154,257

DESIGN FOR A BOTTLE

Richard Estrin, Hewlett, N. Y.

Application July 22, 1947, Serial No. 140,450

Term of patent 14 years

(Cl. D58—6)

To all whom it may concern:

Be it known that I, Richard Estrin, a citizen of the United States of America and resident of 330 Daub Ave., Hewlett, L. I., New York, have invented a new, original, and ornamental Design for Bottles, of which the following is a specification, reference being had to the accompanying drawings, forming a part thereof.

In the accompanying drawings:

Figure 1 shows a front elevation of a bottle showing my new design.

Figure 2 shows a side view thereof, and

Figure 3 shows a top or plan view thereof.

The drawing is shaded to show that the raised U is of contrasting color from the rest of the bottle.

I claim:

The ornamental design for a bottle, as shown.
RICHARD ESTRIN.
